UNITED STATES PATENT OFFICE

JAMES L. BROWNELL, OF KALAMAZOO, MICHIGAN

CIRCUIT CONTROL APPARATUS FOR FLOODLIGHTS AND THE LIKE

Application filed February 7, 1930. Serial No. 426,726.

My invention relates to improvements in multiple electric circuit control means and which although capable of other utilization, will be especially adapted for use in the control of flood lights for effecting many and varied blendings of colors.

Briefly stated,—the invention has for its primary object to provide a novel and improved device of this kind which comprehends a single circuit control element adapted to variably and simultaneously control two or more of a plurality of circuits at one and the same time, and incorporating an actuating means whereby the circuits will be energized in a predetermined sequence.

Another object of the invention is to provide in a device of the character specified, a novel circuit control element whereby a plurality of circuits will be automatically and successively closed in original and reverse sequence.

Another object of the invention is to provide in a device of this kind, a traversing multiple circuit control means and actuating means therefor.

A further object of the invention is to provide a multiple circuit control mechanism for flood lights and the like, which incorporates a movable control element and circuit wire carrying means for maintaining the circuit wires out of the path of said control element.

A still further object of the invention is to provide a multiple circuit control mechanism having a movable control element and support therefor, and carrying means for resistance elements, (which are interposed in the several circuits) said carrying means being associated with portions of the movable element support.

Another object of the invention is to provide a device of this kind which is very simple in construction, relatively inexpensive of manufacture and which will be highly efficient in practical use since it comprehends a minimum number of parts of durable construction,—these being co-related in such a way as to reduce wear and tear to a minimum.

The invention also resides in certain novel

features of construction, combination and arrangement of the various parts and in certain modes of operation,—all of which will be readily apparent to those skilled in the art upon reference to the accompanying drawings in connection with the detailed description thereof to follow.

In the drawings,

Figure 1 is a top plan view of a circuit control device embodying my invention;

Figure 2 is a side elevation view thereof;

Figure 3 is an end elevational view with certain parts shown in cross section;

Figure 4 is a wiring diagram showing the circuits; and,

Figure 5 is an elevational view of the carriage actuating shaft.

Referring specifically to the drawings, wherein the same reference characters have been used to designate the same parts in all views, numeral 2 denotes what is preferably an elongated base of sheet metal having down turned end supporting portions 2^a, down turned supporting flanges 2^b at the sides, and up turned tongues 3 intermediate the portions 2^b.

The tongues 3 at each side of the base carry substantially channel shaped bars 4 of insulating material which extend throughout a substantial portion of the length of the base,—these being secured to tongues 3 by means of screws 5.

Strips 6 of L-shaped cross section are held seated in recesses in the top and inner side surfaces of insulation bars 4 by means of hollow rivets 7 which carry the wires 8. The L-shaped contact strips 6 are arranged in spaced series along each bar 4 and are connected, each to one side of a flood light lamp as indicated in Figure 4 by means of the wire 8 which extends down through one of the rivets 7 as indicated in Figures 1 and 2. As shown the wires 8 are carried lengthwise of the base 2 and extend through transverse recesses formed by cross cleats 9 supported by the base 2 between the tongues 3 and which are held in place by the lower or flanged side of the channel members 4. In this way, the wires 8 are kept out of the path of the circuit-closing member 10 which is disposed there-

above and mounted for movement lengthwise of the base.

Mounted upon the base 2 are bearing members 11, 12 which are spaced in the direction 5 of the length of the base and carry the supporting or guide rod 13 of the slideable circuit closer 10, in addition to its worm drive shaft 14 which latter projects through the bearing 12 and may have a coupling 15 for establishing a driving connection with the reduction gearing of a power unit but which may be supported upon the adjacent surface of base 2 which is denoted at 2^c.

The bearing members 11, 12 have opposed 15 offset ears 11^a, 12^a at each side which are adapted to carry the securing screws 16 of the substantially I-shaped insulation bars 17 which carry the separate resistance coils 18,—of which there is one for each of the flood 20 lights A, B, C, D, E, F, G, and H as shown in the wiring diagram, of Figure 4.

Each coil 18 has one end anchored as at 18^a (Figure 2) to one of the top flanges of its insulating-material carrying bar 17 while 25 the other end is connected to a binding post 20^a, circuited as shown in Figure 4, in one side 21 of an electric circuit,—it being noted that the floodlights A, B, C, etc. are in the other side 22 of said circuit. The posts 20^a 30 are all in circuit through strip 20.

It will be observed that there are two rivets for each of the L-shaped contact strips 6. As has already been mentioned one rivet of each strip carries and forms a guide-like 35 conduit for the wire 8 leading to one of the flood lights A, B, etc. in line 22. The other rivet of each strip 6 may be used to guide the insulated connection from coil 18 to the side 21 of the circuit of strip 20 is not used.

40 The circuit closing member 10 is provided with longitudinal bores receiving the shafts 13, 14 and there is a lug 23 adapted to engage the endless spiral groove 24 of what has been termed the worm shaft 14.

45 Particular attention is directed to the groove 24 which is shown as provided with two spiral flights, one being of what might be termed a right hand thread and the other of left hand thread,—these flights being designated as at 24^a and 24^b. Since the two groove flights are connected, the contact member 10 will be driven back and forth between the pairs of insulating bars 6, 17 which carry, respectively, the series of L-shaped contact 50 strips 6 and resistance coils 18 of the circuits of the respective flood lights, A, B, C, etc.

Secured to the base of the member 10 by means of screws 26 is a cross block 27 which is recessed to seat the bottom of the member 6 and carries the contact or bridging members 28 which are secured to the cross block 27 by screws 29. The contact members 28 have reverted portions 30 arranged to successively engage the strips 6 and lateral portions 31 adapted to engage the bare convolu-

tions of the coils 18 upon the I-shaped bars 17.

From the foregoing description, the operation of the device will be apparent to those skilled in the art but may be summarized as follows:

Assuming the circuit closer 10 to be in the position shown in Figures 1 and 2, the motor 35 (Figure 4) is started causing the carriage to move toward the left (Figure 1). This means that the flow of current from the source of supply 36 through line 21 will pass in undiminished strength directly to the flood light H in the other side 22 of the circuit. However, respecting the flood light D whose contact strip 6 is directly opposite the contact strip of flood light H (and whose resistance coils 18 are also in opposition to one another as shown),—will be but dimly illuminated at first for the reason that the current from the supply line 21 must flow through the coil 18, bridging strip 28 and contact strip 6 before reaching the line 22 containing the flood light D. However, as the member 10 moves in its leftward direction the resistance in circuit H increases whereas the resistance in circuit D decreases, it being noted that the right end of the H circuit coil 18 is connected to line 21 whereas the left end of the H circuit coil is connected thereto. Of course, the flood lights D and H will be of different colors,—this being true of the other flood lights. Manifestly, many and varied color effects will be produced as the circuit closing member 10 moves in its leftward path with its bridging member 28 closing the circuits of two lamps simultaneously by means of the bridging elements 28 whereby through the coils 18 to progressively dim one flood light and progressively intensify the light of another lamp.

When the lug 23 of the carrier 10 reaches the leftmost portion or end of groove flight 24^a it is automatically carried into the oppositely spiraled groove flight 24^b which causes the member 10 to move towards the right again producing a reverse control of the floor light circuits and the resulting color effects and changes in inverse sequence.

Having thus described my invention, what I claim as new and desire to secure by Letters Patent is:

1: A multiple circuit control mechanism comprising a base, a movable member, supporting and guide means for said member carried by said base, separate pairs of resistance and contact elements arranged in spaced series paralleling the path of movement of said movable member, each pair being adapted to be included in a circuit to provide a gap therein, and bridging means carried by said movable element for connecting said contact and resistance elements.

2. A multiple circuit control mechanism comprising a base, a movable member, supporting and guide means for said member

carried by said base, separate resistance and contact elements disposed at each side of said movable member and arranged in spaced lineal series paralleling the path of movement of said member, the adjacent resistance and contact elements of each series being adapted to be included in separate circuits to provide gaps therein, and separate bridging means carried by opposite sides of said movable element for bridging the adjacent contact and resistance elements to close the gaps therebetween.

3. A multiple circuit control mechanism comprising a base, a movable member, supporting and guide means for said member carried by said base, a series of spaced resistance elements and a laterally spaced series of spaced contact elements adjacent the path of movement of said movable member and paralleling the same, corresponding ones of said resistance and contact elements being adapted to be included in one of a plurality of circuits to provide a gap therein, bridging means for said gaps and being carried by said movable element, and motivating means for said movable element.

4. The combination set forth in claim 3,— and said motivating means having a reversing drive connection with said movable member for automatically effecting a predetermined movement thereof in opposite directions.

5. The combination set forth in claim 2 and said resistance elements at one side of said movable member having circuit connection points lineally spaced from the circuit connection points of the resistance elements at the opposite side of said movable member.

6. A multiple circuit control mechanism comprising a base, a movable member, supporting an actuating means for said member carried by said base, resistance and contact units carried by said base and adjacent the path of said movable member, said resistance and contact units being spaced from one another to provide a circuit gap, and separating cleats for circuit wires disposed out of the path of movement of said movable member.

7. In a multiple circuit control device, a base, spaced bearings mounted upon said base, a slidable circuit control element, a supporting guide therefor carried by said bearings, actuating means for said circuit control element carried by said bearings, resistance unit carrying bars at each side of said guide and spaced therefrom, said bearings providing a detachable support for said bars, resistance units carried by said bars and arranged in spaced lineal series, opposed resistance units of the respective bars having circuit take-off leads at lineally spaced points, a contact carrying bar adjacent each of said resistance unit carrying bars, spaced contacts on said contact strip carrying bar adjacent the

respective resistance units of said aforementioned bars, and corresponding ones of said contact strips and resistance units being adapted to be disposed in the same electrical circuit and providing a gap therein, and bridging means carried at each side of said circuit control element for closing the gaps between the respective resistance units and contact strips.

8. In a multiple circuit control device, a base, spaced bearings mounted upon said base, a slidable circuit control element, a supporting guide therefor carried by said bearings, actuating means for said circuit control element carried by said bearings, resistance unit carrying bars at each side of said guide and spaced therefrom, said bearings providing a detachable support for said bars, resistance units carried by said bars and arranged in spaced lineal series, opposed resistance units of the respective bars having circuit takeoff leads at lineally spaced points, a contact carrying bar adjacent each of said resistance unit carrying bars, spaced contact strips on said contact bars adjacent the respective resistance units of said aforementioned bars,

and corresponding ones of said contact strips and resistance units being adapted to be disposed in the same electrical circuit and providing a gap therein, bridging means carried at each side of said circuit control element for closing the gaps between the respective resistance units and contact strips, a series of

upstanding ears at each side of said base and supporting said contact-carrying bars, and transversely disposed wire guiding cleats supported by said base beneath said contact carrying bars intermediate opposed ones of said ears.

9. In a multiple circuit control device, a base, spaced bearings mounted upon said base, a slidable circuit control element, a supporting guide therefor carried by said bearings, actuating means for said circuit control element carried by said bearings, resistance unit carrying bars at each side of said guide and spaced therefrom, said bearings providing a detachable support for said bars, resistance units carried by said bars and arranged in spaced lineal series, opposed resistance units of the respective bars having circuit takeoff leads at lineally spaced points, a contact carrying bar adjacent each of said resistance unit carrying bars, spaced contact strips on said contact bars adjacent the respective resistance units of said aforementioned bars,

and corresponding ones of said contact strips and resistance units being adapted to be disposed in the same electrical circuit and providing a gap therein, bridging means carried at each side of said circuit control element for closing the gaps between the respective resistance units and contact strips, a series of

upstanding ears at each side of said base and supporting said contact-carrying bars, and transversely disposed wire guiding cleats supported by said base beneath said contact carrying bars intermediate opposed ones of said ears.

9. In a multiple circuit control device, a base, spaced bearings mounted upon said base, a slidable circuit control element, a supporting guide therefor carried by said bearings, actuating means for said circuit control element carried by said bearings, resistance unit carrying bars at each side of said guide and spaced therefrom, said bearings providing a detachable support for said bars, resistance units carried by said bars and arranged in spaced lineal series, opposed resistance units of the respective bars having circuit takeoff leads at lineally spaced points, a contact carrying bar adjacent each of said resistance unit carrying bars, spaced contact strips on said contact bars adjacent the respective resistance units of said aforementioned bars,

and corresponding ones of said contact strips and resistance units being adapted to be disposed in the same electrical circuit and providing a gap therein, bridging means carried at each side of said circuit control element for closing the gaps between the respective resistance units and contact strips, a series of

upstanding ears at each side of said base and supporting said contact-carrying bars, and transversely disposed wire guiding cleats supported by said base beneath said contact carrying bars intermediate opposed ones of said ears.

10. In a multiple circuit control device, a base, spaced bearings mounted upon said base, a slidable circuit control element, a supporting guide therefor carried by said bearings, actuating means for said circuit control element carried by said bearings, resistance unit carrying bars at each side of said guide and spaced therefrom, said bearings providing a detachable support for said bars, resistance units carried by said bars and arranged in spaced lineal series, opposed resistance units of the respective bars having circuit take-off leads at lineally spaced points, a contact carrying bar adjacent each of said resistance unit carrying bars, spaced contacts on said contact strip carrying bar adjacent the

ing the latter and providing circuit wire take-off connections and conduits for such wires.

10. In a multiple circuit rheostat control device for flood-lamp systems or the like, a base, two laterally spaced series of spaced resistance units, a laterally spaced contact strip for each resistance unit and forming a circuit gap therebetween, corresponding ones of said resistance units of each series having lineally spaced circuit takeoff points, and a movable circuit closer having means for bridging said gaps.

11. In a multiple circuit rheostat control device for flood-lamp systems or the like, a base, two laterally spaced series of spaced resistance units, a laterally spaced contact strip for each resistance unit and forming a circuit gap therebetween, corresponding ones of said resistance units of each series having lineally spaced circuit takeoff points, a movable circuit closer having means for bridging said gaps, and an automatically reversible drive means for said circuit closer for moving same back and forth along said series of resistance units and contact strips.

12. In a multiple circuit rheostat control device for flood-lamp systems or the like, a base, two laterally spaced series of spaced resistance units, a laterally spaced contact strip for each resistance unit and forming a circuit gap therebetween, corresponding ones of said resistance units of each series having lineally spaced circuit takeoff points, a movable circuit closer having means for bridging said gaps, guide means for said circuit closer, and said guide means providing a support for said resistance units.

13. In a multiple circuit rheostat control device for flood-lamp systems or the like, a base, two laterally spaced series of spaced resistance units, a laterally spaced contact strip for each resistance unit and forming a circuit gap therebetween, corresponding ones of said resistance units of each series having lineally spaced circuit takeoff points, a movable circuit closer having means for bridging said gaps, guide means for said circuit closer, said guide means providing a support for said resistance units, a driven shaft adjacent said guide and having an endless groove comprising opposed spiral flights, and a lug extending from said carrier and engaging in said groove.

14. In a multiple circuit rheostat control device for flood-lamp systems or the like, a base, two laterally spaced series of spaced resistance units, a laterally spaced contact strip for each resistance unit and forming a circuit gap therebetween, corresponding ones of said resistance units of each series having lineally spaced circuit takeoff points, a movable circuit closer having means for bridging said gaps, a mounting bar for the contact strips of each series of resistance

units, and ears projecting from said base for supporting said mounting bars.

15. In a multiple circuit rheostat control device for flood-lamp systems or the like, a base, two laterally spaced series of spaced resistance units, a laterally spaced contact strip for each resistance unit and forming a circuit gap therebetween, corresponding ones of said resistance units of each series having lineally spaced circuit takeoff points, a movable circuit closer having means for bridging said gaps, a mounting bar for the contact strips of each series of resistance units, ears projecting from said base for supporting said mounting bars, and hollow lead wire-securing and conduit-providing securing rivets for said contact strips extending through said mounting bars.

16. In a multiple circuit rheostat control device for flood-lamp systems or the like, a base, two laterally spaced series of spaced resistance units, a laterally spaced contact strip for each resistance unit and forming a circuit gap therebetween, corresponding ones of said resistance units of each series having lineally spaced circuit takeoff points, a movable circuit closer having means for bridging said gaps, a mounting bar for the contact strips of each series of resistance units, ears projecting from said base for supporting said mounting bars, hollow lead wire-securing and conduit-providing securing rivets for said contact strips extending through said mounting bars, lead wire guides upon said base beneath said mounting bars and certain of said ears being opposed to one another and engaging the ends of said lead wire guides.

17. In a multiple circuit control device, a longitudinally arranged support for a plurality of coiled resistance elements, a slidable circuit closer traversing said resistance elements, guide means for the circuit closer carried by the support, contact elements corresponding in length substantially to the traversable length of the resistance elements by the circuit closer, and power driven means for imparting a continuous reciprocating movement to said circuit closer along said resistance and contact elements.

18. In a multiple circuit control device, a longitudinally arranged support for a plurality of coiled resistance elements, a slidable circuit closer traversing said resistance elements, guide means for the circuit closer carried by the support, contact elements corresponding in length substantially to the traversable length of the resistance elements by the circuit closer, and a reversely threaded rotating member having communicating grooves for imparting a reciprocatory traversing movement to said circuit closer.

19. In a multiple circuit control device, a longitudinal arranged support for a plurality of resistance elements, a slidable circuit closer traversing said resistance elements,

guide means for the circuit closer carried by the support, contact elements traversable by the circuit closer, and a longitudinally disposed uni-directionally rotatable element having means cooperating therewith for imparting a reciprocatory traversing movement to said circuit closer.

In testimony whereof I affix my signature.
JAMES L. BROWNELL.
